CLAIM

(21) Appl. No.: **29/394,945**

The ornamental design for a plush toy for enhanced emotional learning, as shown and described.

(22) Filed: **Jun. 23, 2011**

DESCRIPTION

(51) **LOC (9) Cl. 21-01**

FIG. 1 is an upper left front perspective view of a plush toy for enhanced emotional learning of the present invention; FIG. 2 is a front elevational view of the toy of FIG. 1; FIG. 3 is a left side elevational view of the toy of FIG. 1; FIG. 4 is a rear elevational view of the toy of FIG. 1; FIG. 5 is a right side elevational view of the toy of FIG. 1; FIG. 6 is a top plan view of the toy of FIG. 1; and, FIG. 7 is a bottom plan view of the toy of FIG. 1.

(52) **U.S. Cl. D21/628; D21/621**

The broken line showing of the plush toy for enhanced emotional learning is for the purpose of illustrating portions thereof, and forms no part of the claimed design.
